ATTYS-

UNITED STATES PATENT OFFICE.

BENJAMIN SCARLES, OF CLINTON, MASSACHUSETTS, ASSIGNOR TO THE
CLINTON WIRE CLOTH COMPANY, OF SAME PLACE

METALLIC LATHING.

SPECIFICATION forming part of Letters Patent No. 387,740, dated August 14, 1888.

Application filed May 1, 1888. Serial No. 272,500. (No model.)

To all whom it may concern:
Be it known that I, BENJAMIN SCARLES, a citizen of the United States, residing at Clinton, in the county of Worcester, State of Massachusetts, have invented a certain new and useful Improvement in Metallic Lathing, of which the following is a description sufficiently full, clear, and exact to enable any person skilled in the art or science to which said invention appertains to make and use the same, reference being had to the accompanying drawings, forming part of this specification, in which—

Figure 1 is a top plan view of a piece of my improved metallic lathing; Fig. 2, a like view showing a modification in the construction, and Fig. 3 a vertical transverse section taken on line *x* *x* in Fig. 2.

Like letters and figures of reference indicate corresponding parts in the different figures of the drawings.

My invention relates to that class of metallic lathing in which the wire-cloth body for receiving the imposed plastering is provided with metallic furring-strips to adapt it for ready use without the employment of independent furring; and it consists in certain novel features, as hereinafter fully set forth and claimed, the object being to produce a more desirable article of this character than is now in ordinary use.

The nature and operation of the improvement will be readily understood by all conversant with such matters from the following explanation.

In the drawings, A represents the body of the lathing, and B the furring, the body being composed of wire-cloth, which may be of any suitable gage or size of mesh, the wires, meshes, and furring being purposely enlarged in the drawings to illustrate the improvement to better advantage.

The furring is composed of a strip of sheet metal which is folded on a line extending longitudinally through its center until approximately U-shaped in cross-section, and provided at intervals on either edge or side with laterally-projecting flanges *m*, which are formed integral or in one piece with the body of the furring. These flanges may stand opposite each

other, as shown in Figs. 2 and 3, or be formed alternately at opposite sides of the strip, as shown in Fig. 1, the latter construction being deemed preferable, as it separates the attaching-points to a greater distance from each other and distributes the strain on the cloth accordingly. It also prevents closing the meshes of the cloth at the points where the flanges are inserted as fully as when the flanges are placed opposite each other, and hence the plastering will adhere better.

In attaching the furring-strip it is placed on the cloth and arranged transversely or at right angles to the line of the web, or longitudinally of the web, as preferred, after which the flanges *m* are passed through its meshes and bent downward over the adjacent filling-wires, each flange embracing one or more of said wires, preferably but one.

It will be understood that the web of cloth is provided with the furrings throughout its entire length, the strips being arranged in parallelism with each other and placed, preferably, about six or seven inches apart, the distance between the strips being, however, varied according to the texture of the wire or nature of the work.

When the web has been provided with furring-strips, as described, it is wound into a roll and constitutes a ready-made fire-proof lathing, which may be used without furring the walls, ceiling, or other portion of the building to which it is attached. It will also be understood that the lathing may be secured to the building by staples, nails, or in any other suitable manner.

Having thus explained my invention, what I claim is—

1. As an improved article of manufacture, a metallic furring-strip provided at intervals at its edges or sides with flanges for attaching it to wire-cloth, the body of said strip being approximately U-shaped in cross-section and the flanges integral therewith, substantially as set forth.

2. As an improved article of manufacture, a metallic furring-strip having a body which is approximately U-shaped in cross-section and provided at its edges or sides with flanges for attaching it to wire-cloth, said flanges be-

ing integral with said body and arranged alternately or in such manner as not to stand opposite each other, substantially as and for the purpose set forth.

5 3. In a metallic lathing, the combination of the wire-cloth, A, and furring-strip B, provided with flanges *m*, the body of said strip being approximately U-shaped in cross sec-

tion and secured to the cloth by the flanges bent downward over the wires of the cloth, substantially as shown and described.

BENJAMIN SCARLES.
